US0D1049256S

(12) **United States Design Patent** (10) **Patent No.:** **US D1,049,256 S**
(45) **Date of Patent:** **** Oct. 29, 2024**

(54) **MAGNETIC BUILDING TILE**

(71) Applicant: **Ningbo Gemmicc Toys Co., Ltd.**,
Yuyao (CN)

(72) Inventor: **Hongzhi Shen**, Yuyao (CN)

(73) Assignee: **Ningbo Gemmicc Toys Co., Ltd.**,
Yuyao (CN)

(**) Term: **15 Years**

(21) Appl. No.: **29/842,799**

(22) Filed: **Jun. 16, 2022**

(30) **Foreign Application Priority Data**

Mar. 22, 2022 (CN) 202230150520.6

(51) **LOC (14) Cl.** **21-01**

(52) **U.S. Cl.**

USPC **D21/404**; D21/491

(57) **CLAIM**

The ornamental design for a magnetic building tile, as shown and described.

DESCRIPTION

FIG. 1 is a front, bottom, right side perspective view of the magnetic building tile, showing my new design;

FIG. 2 is a back, top, left side perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
